UNITED STATES PATENT OFFICE.

ANTHONY DI SALVATORE, OF SCOTIA, NEW YORK.

LADDER AND SAFETY-LOCK.

1,352,055.

Specification of Letters Patent. Patented Sept. 7, 1920.

Application filed April 19, 1920. Serial No. 375,044.

To all whom it may concern:

Be it known that I, ANTHONY DI SALVATORE, a citizen of the United States, residing at Scotia, in the county of Schenectady and State of New York, have invented certain new and useful Improvements in Ladders and Safety-Locks; and I do declare the following to be a full, clear, and exact description of the invention, such as will enable others skilled in the art to which it appertains to make and use the same.

This invention relates to an improved ladder such as is commonly used in stores for reaching articles placed upon high shelves. It is customary to provide a ladder which is slidably mounted upon upper and lower tracks so that the ladder may be moved longitudinally of the shelves to the point where it is to be used. It has been found exceedingly dangerous to provide a ladder of this type without a lock which will prevent moving of the ladder while in use as it often happens that when one person is standing upon the ladder another who wishes to use the ladder will move the ladder thus causing the person standing upon the ladder to fall. Various locks have been provided for locking a ladder of this type but locks now in use are all so constructed that they may be easily released from the flooring, and if the person who wishes to use the ladder does not look to see if it is already in use the lock often is released and the ladder removed, thus causing the person standing upon the ladder to fall.

In order to overcome the objections noted above the lock which forms the subject matter of this invention has been provided, the lock being so constructed that it may be securely locked by the person using the ladder thus preventing another who wishes to use the ladder from releasing the lock at the first attempt. If the lock does not release at the first attempt the person who desires to use the ladder will naturally look up to see what is wrong with the lock and will then observe that the ladder is already in use.

Another object of the invention is to so construct this lock that the person using the ladder may release the lock in case the user desires to move the ladder without getting off of it and to further so construct the lock that it may be moved to an operative position or inoperative position from a number of positions upon the ladder.

Another object of the invention is to so construct the lock and actuating means that it may be released from the floor in case a user of the ladder forgets to release the lock when finished using the ladder.

Another object of the invention is to provide a lock which is so constructed that it may be applied to ladders already installed thus making it unnecessary to provide a special construction of ladder.

This invention is illustrated in the accompanying drawings wherein:

Figure 1 is a perspective view of the upper end portion of a ladder having the improved locking structure connected therewith.

Fig. 2 is a view showing the ladder in elevation and locking at the under or rear side of the ladder.

Fig. 3 is a fragmentary view in elevation with the locking device in an inoperative position.

This lock is used in connection with a ladder indicated in general by the numeral 10 and provided at its upper end with a cross-head 11 carrying the truck or carriage 12 which will be provided with the usual wheels 13 for engaging the upper track 14 extending in front of the shelves. This is a conventional construction and it is to be understood that the ladder may be provided with either this type of head and carriage or any other conventional type for slidably connecting the ladder with the upper track. It is also to be understood that the lower ends of the side rails may be provided with floor engaging rollers which will be mounted upon floor tracks if so desired. A wire or cable 15 extends beneath the track 14 between the upper ends of the side rails of the ladder and will be engaged by a gripping jaw 16 which is pivotally connected with a supporting bracket 17 secured to the upper step of the ladder. This jaw is provided with a lever extension 18 which carries the usual weight 19 for swinging the jaw upwardly and causing the cable 15 to be tightly gripped between the jaw 16 and the overhanging end portion or stationary jaw 20 of the bracket 17. A line 21 is connected with the jaw and extends downwardly along the under side of the ladder and has its lower end connected with a ring or eye 22 secured to one of the lower steps of the ladder.

This is a conventional type of grip for engaging the cable 15 and locking the

- ladder and as stated above it often happens that a person who desires to use the ladder will grasp the line 21 and draw it downwardly thus releasing the ladder without looking up to see if the ladder is in use. This places the person using the ladder in danger and it is to overcome the objection noted that the lock that will now be described has been provided.
- 10 A line 23 is passed through conductor tubes 24 which are secured to the underface of one of the side rails and has its upper end extending from the upper end of the upper tube 24 and provided with a ring or other similar device 25 which will prevent this line from slipping into the upper tube.
- 15 The lower end of this line extends into a tubular housing 26 and will be provided with a similar ring for preventing the line from being drawn up into the lower tube 24. In order to permit access to the lower end of this line when necessary the housing 26 has been provided with a side opening which will normally be closed by the door 27.
- 20 Side lines 28 extend from the line 23 between the conductor tubes 24 and these side lines 28 are passed through shorter tubes 29 which are secured to the steps of the ladder and terminate a short distance from the tongues or arms 30 which extend from the brackets 31 secured to the steps. These lines 28 are connected with the line 21 and it will thus be seen that when the line 23 is drawn upon from its upper or lower end, the lines 28 will be drawn transversely of the ladder and the line 21 will be moved thus drawing the abutment balls 32 from a position above the arms 30 to a point beyond the free ends of the arms.
- 25 When in use the tubes 29 and the brackets 31 will be secured to certain of the ladder steps and preferably at about seven or eight steps apart. The tubes 24 will then be put in place with their adjacent ends terminating in spaced relation above and below the steps carrying the brackets 31 and tubes 29 and the housing 26 will be connected with the ladder to close the lower end of the last tube 24. The line 23 will
- 30 then be passed through the tubes with its lower end extending into the housing and carrying a ring and its upper end extending out of the upper end of the upper tube for about a foot. The abutment balls 32 will
- 35 be placed upon the line 21 and secured at the proper points by the set screws 33 so that these balls will be positioned to engage the upper edges of the arms 30 and the rear edge portions of the steps and prevent downward movement of the line 21 when the line is in the position shown in Figs. 1 and 2. Therefore when a person is using the ladder they may climb to the desired point and may then swing the line 21 to position the abutment balls as shown in Figs. 1 and 2 and
- 40 thus prevent the ladder from being moved until the line has been swung to the position shown in Fig. 3. If the user of the ladder desires to move the same without leaving the ladder it is simply necessary to grasp the line 23 either by means of the ring 25 or at a point between two of the tubes 24 and thus draw upon the line and by so doing draw the lines 28 outwardly. This will cause the line 21 to be swung to the position shown in Fig. 3 and the locking balls may then pass between the arms 30 and tubes 29. The line 21 may then be drawn downwardly to swing the jaw 16 out of engagement with the cable 15. After the ladder has been moved to the desired position the line 21 will be released and the weight 45 will cause the lock to return to the operative position. If a person desires to use the ladder the line 21 will be grasped and pulled downwardly and if the ladder is not in use the abutment balls will pass between the arms 30 and tubes 29 and permit the lock to be released. If however, the ladder is in use and the line swung to the position shown in Fig. 2 the line will be held against downward movement and when the line does not move to release the lock the person desiring to use the ladder will look up to see what has prevented the lock from 50 releasing. The person using the ladder will then be noticed and the second party will wait until the person using the ladder has finished; if the previous user has left the ladder without releasing the locking device, it is simply necessary to open the door 27 and the ring at the lower end of the line 23 can then be grasped and the line pulled downwardly to draw the lines 28 outwardly and thus release the lock. It will thus be 55 seen that there has been provided a device by means of which the line 21 may be held against movement to release the locking jaw 16 and thus danger of injury to persons using the ladder prevented.
- 55 What is claimed is:
1. A slidably mounted ladder, a lock for releasably holding the ladder against slid-
able movement, a line connected with the lock for moving the lock to an inoperative position, an abutment element carried by the ladder, an abutment element carried by the line, for engaging the abutment ele-
ments of the ladder to retain the line against downward movement, and means carried by the ladder and connected to the line for drawing the line to one side and permitting the abutment carried thereby to pass the abutment carried by the ladder.
- 110
- 115
- 120
- 125
- 130
2. A traveling ladder, a lock carried by the ladder to retain the ladder against move-
ment, abutment brackets carried by the ladder, an actuating line for said lock, abut-
ment elements carried by the line for en-
gaging the abutment brackets to hold the

line against downward movement, and means carried by the ladder and engaging the line for drawing the line to one side to position the abutments thereof out of engagement with the abutment brackets and permit movement of the line to release said lock.

3. A traveling ladder, a lock for the ladder, a line for moving the lock to a releasing position, abutment brackets carried by the ladder, abutment balls carried by the line for engaging the brackets, an actuating line slidably connected with the ladder and extending longitudinally thereof, and side lines extending from the actuating line and connected with the first mentioned line to draw the first mentioned line to one side when the actuating line is drawn upon and position the balls out of engagement with the brackets.

4. A traveling ladder, a lock for the same, a line connected with the lock for releasing the same, brackets connected with certain of the steps of said ladder and having abutment arms extending in spaced relation to the steps, abutment balls carried by the line for engaging the arms and holding the line against downward movement when the line is positioned to extend between the arms and the ladder steps, conductor tubes connected with one of the side rails of the ladder and terminating in spaced relation above and below the steps carrying the brackets, conductor tubes connected with the steps carrying the brackets, and side lines connected with the actuating line between the tubes of the side rail and extending through the tubes of the steps and connected with the first mentioned line.

5. The combination with a traveling ladder, a lock for the ladder, and a line connected with the lock for moving the lock to an inoperative position, of conductor tubes

connected with one of the side rails of the ladder and having their adjacent ends terminating in spaced relation, a housing enclosing the lower end of the lower tube and provided with a normally closed inlet opening, an actuating line extending through the tubes with its lower end extending into the housing and its upper end extending in the upper end of the upper tube, an abutment carried by one of the steps of the ladder, an abutment carried by the first mentioned line for engaging the abutment of the ladder step, and a side line connected with the actuating line between the tubes and connected with the first mentioned line adjacent the abutment thereof to draw the first mentioned line to one side and position the abutment thereof out of engagement with the ladder abutment.

6. The combination with a traveling ladder, a lock for releasably holding the ladder against sliding movement and a line for moving the lock to an inoperative position, of an abutment carried by the ladder, an abutment carried by the line for engaging the ladder abutment to hold the line against movement to release the lock, and means connected with the first mentioned line for drawing the first mentioned line to position the abutment thereof out of engagement with the ladder abutment and permit movement of the first mentioned line to release the lock.

7. A traveling ladder, a lock for the same, an actuating line for the lock, means holding the line against movement to release the lock when the line is in its normal position, and means for moving the line out of its normal position for movement to release the lock.

In testimony whereof I have hereunto set my hand.

ANTHONY DI SALVATORE.
